FIG. 1

FIG. 2.

FIG. 3.

FIG. 4.

Inventor

John N. Nenonen

By

Attorney

UNITED STATES PATENT OFFICE.

JOHN N. NENONEN, OF ABERDEEN, WASHINGTON.

FUSE.

Application filed June 19, 1923. Serial No. 646,347.

To all whom it may concern:

Be it known that I, JOHN N. NENONEN, a citizen of Finland, residing at Aberdeen, in the county of Grays Harbor and State of Washington, have invented certain new and useful Improvements in a Fuse, of which the following is a specification.

This invention relates to fuse plugs and more particularly to an improved structure for fuse plugs adapted to readily disclose to an observer the condition of the plug with respect to the fusible element therein.

One of the objects of the invention is to provide a fuse plug in which the defective condition of the plug may be easily detected after the fusible wire blows out.

Other objects of the invention will appear upon consideration of the following detailed description and accompanying drawings in which:

Figure 1 is a cross section through the plug,

Figure 2 is a plan view,

Figure 3 is a similar view showing the signal disc, and

Figure 4 is a perspective view of the warning signal.

The plug 1 comprises the housing of the ordinary type except that in the present form one wall of the housing on the interior thereof is provided with a recess 2. The side terminal 3 is mounted on the shank of the plug and is screwthreaded in the usual manner, whereby the plug may be mounted in position. The top of the plug is provided with a removable cap or ring 4 adapted to hold a transparent panel 5 constructed of mica or other suitable transparent material, whereby an observer may view the interior of the plug housing. A centrally located spring rod is mounted within the housing and this spring rod, indicated at 6, has its lower end extended through the end of the housing and carries the bottom terminal plate 7. This rod 6 is of spring material and has its upper end provided with a colored disc 8. The disc is preferably of a bright color which may be readily observed through the transparent panel 5. A fusible link 9 is mounted in the recess 10 in the housing and is soldered to the side terminal 3 and the spring rod 6. Since this link is relatively short, the spring rod 6 is thereby pulled over

to one side of the housing so that the disc is lodged in the recess 2.

The fusible link 9 is constructed of the usual fusible material and when an excess current occurs it will be obvious that the link will be broken so that the spring rod 6 will spring to the position shown by dotted lines in Figure 1, thus causing the colored disc 8 to be exposed in a position where it will be readily observed through the transparent panel 5, thus indicating to the observer that the plug is defective.

Minor changes may be made in the details of construction without departing from the spirit of the invention or the scope of the claims hereunder appended.

What I claim is:

1. A fuse plug comprising a hollow body having its wall provided with a recess, a side terminal mounted on the body, a bottom terminal on the end of the body, a spring rod connected to the said bottom terminal, and adapted to normally extend centrally through the said body, and a fusible link connected to the said side terminal and extending through the body and joined to the said spring rod for maintaining the spring rod under a tension whereby the free end of the rod will be held resiliently in the said recess.

2. A fuse plug comprising a plug body having a hollow interior, the wall of the body being provided with a recess and an opening, a transparent cap for one end of the said body, the opposite end of the body being provided with a bottom terminal, a side terminal on the said body, a spring rod connected to the bottom terminal and extending through the said hollow body, a colored disc carried on the free end of the said rod, and a fuse link connected to the said side terminal and projecting through the said opening in the body to be connected to the said spring rod whereby it will releasably hold the said spring rod in a curved position to maintain the said colored disc in the said recess until the said link is released.

In testimony whereof, I have affixed my signature in the presence of two witnesses.

JOHN N. NENONEN.

Witnesses:

A. K. JOHNSEN,
SIDNEY REHM.
